PAGE 7

FIG. 7

Fig. 8.

Fig. 9.

Figs. 1-6 each show a plan view of a segment of a panel of plastic sheet material or similar article showing our new design.

Fig. 7 is a diagram showing how the segments of design illustrated in Figs. 1-6 are arranged to form the complete panel.

Fig. 8 is a plan view of a segment of the panel shown in actual scale.

Fig. 9 is an enlarged plan view showing the ornamentation in greater detail.

We claim:

The ornamental design for a panel of plastic sheet material or similar article, as shown.
